CLAIM

The ornamental design for a braid protector for horse as shown and described.

DESCRIPTION

Fig. 1.1 is an environmental perspective view of a braid protector for horse in accordance with the present design, in an assembled state;

Fig. 1.2 is an elevation view of the braid protector for horse in an unassembled state; and

Fig. 1.3 is a perspective view of the braid protector for horse in an assembled state.

The broken line showing of a horse in the Fig. 1.1 view is for illustrative purposes only and forms no part of the design claim.
